UNITED STATES PATENT OFFICE

145,072

DESIGN FOR A MOTOR DRIVEN VEHICLE

Glenn F. Doyle, Dearborn, Mich.

Application March 16, 1945, Serial No. 118,513

Term of patent 7 years

(Cl. D14—3)

To all whom it may concern:

Be it known that I, Glenn F. Doyle, a citizen of the United States, residing at Dearborn, Wayne County, Michigan, have invented a new, original, and ornamental Design for a Motor Driven Vehicle, of which the following is a specification, reference being had to the accompanying drawings, forming a part thereof, in which

Fig. 1 is a top plan view, Fig. 2 is a side elevational view, Fig. 3 is a front elevational view and

Fig. 4 is a top perspective view drawn to a larger scale than Figs. 1 to 3, inclusive. The several views show a motor driven vehicle embodying my design.

The characteristic features of my design are shown by means of full lines in the drawings.

I claim:

The ornamental design for a motor driven vehicle, as shown and described.

GLENN F. DOYLE.
